UNITED STATES PATENT OFFICE.

JOHN C. BIRD, OF BATTLE CREEK, MICHIGAN, ASSIGNOR TO UNION STEAM PUMP COMPANY, OF BATTLE CREEK, MICHIGAN.

VALVE-GEAR.

No. 857,579.

Specification of Letters Patent.

Patented June 25, 1907.

Application filed September 15, 1905. Serial No. 278,653.

To all whom it may concern:

Be it known that I, JOHN C. BIRD, a citizen of the United States, residing at Battle Creek, in the county of Calhoun and State of Michigan, have invented certain new and useful Improvements in Valve-Gear, of which the following is a specification.

This invention relates to improvements in valve gear.

10 My improved valve gear is particularly adapted for use on a pair of single pumping engines, and I have illustrated the same adapted thereto although it is advantageous for use in other relations.

15 The objects of this invention are, first, to provide an improved valve gear for duplexing a pair of single engines whereby their relative movement is controlled or timed and the short-stroking of one by the other reduced to a minimum. Second, to provide an improved valve gear for duplexing a pair of single independent engines by means of which either of the engines may be thrown out of operation, the other remaining in operation. Third, to provide an improved valve gear which is simple in structure and not likely to get out of repair.

Further objects, and objects relating to structural details, will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawing forming a part of this specification, in which,

40 Figure 1 is a detail side elevation view of a structure embodying the features of my invention. Fig. 2 is a detail plan view thereof. Fig. 3 is an enlarged detail side elevation view, showing the connections and arrangement of the parts for operating the valves. Fig. 4 is an enlarged detail sectional view taken on a line corresponding to line 4-4 of Fig. 3. Fig. 5 is a detail side elevation view showing the structure of the coupling for the 45 synchronizing bar to the piston rod. Fig. 6 is a detail sectional view taken on a line corresponding to line 6-6 of Fig. 5. Figs. 7, 8, 9, and 10 are diagrammatic views showing the operation of the valve gear.

In the drawings the sectional views are taken looking in the direction of the little arrows at the ends of the section lines, and similar letters of reference refer to similar parts throughout the several views.

Referring to the drawings, A A represent the engine cylinders. These cylinders are provided with suitable valves, the details of which are not here illustrated as they form no part of this invention.

B B represent the pumps. The cylinders A and the pumps B are connected by the tie rods C, preferably four to each cylinder and pump.

D D are the piston rods.

Valve stems H H project toward the pump cylinders and are operated by the rock levers E''. These rock levers E'' are pivoted on the brackets G by suitable pivot pins e'. The heads e'' of the rock levers project between the tappets H' of the valve stem, so that as the lever is rocked the valve is shifted. The lever E'' is arranged through the coupling sleeve E' which is secured by the pivot e to the sleeve E which is slidably mounted on one of the lower tie-rods C. The sleeve E is shifted by the synchronizing bar F, which is connected thereto by the coupling sleeve f through which the bar is arranged, the coupling sleeve f being secured by the pivot f' to the sleeve E.

The bar F is operated by the piston rods D, the bar being connected thereto by the brackets D' on the piston rods. The bar F is secured to the brackets by means of the coupling sleeves F' through which it is arranged. The sleeves F' are secured to the brackets by the pins d. This mechanism is duplicated for each pump, so that, as the synchronizing bar is carried back and forth by the piston rods, the valve stems are shifted through the connections described.

When it is desired to throw one of the engines out of operation, the sleeve F' of that pump is disconnected from the piston rod by withdrawing the pin d from the bracket D' and securing the sleeve by the pin d''' to the bracket D''' on one of the tie rods. By thus disconnecting one end of the bar F from one of the piston rods, its movement is so limited that it does not actuate the valve of that engine, although the other engine may still operate. The sleeves F' are, for convenience in manipulation, made in the form of

handles, as is illustrated. For convenience in manipulating the pin d , it is preferably adjustably secured to the bracket D' . (See Figs. 5 and 6.) This is accomplished by means of the stud d' on the pin which is arranged in the slot D'' . The seat d'' is formed at the upper end of the slot to receive the stud d' , whereby the pin d is locked in its upper position. To prevent the rod F slipping from the sleeves f and F' , a pin or set screw f'' is provided. (See Fig. 4.) This secures the rod to one of the sleeves and allows it to slip within the others. By thus arranging the parts, the valve mechanism of each engine is operated largely by the engine itself, and not by its neighbor, as is customary in duplex engines, the action of one engine on the valve of its neighbor being only sufficient to keep the pumps in step. This reduces the possibility of one cylinder short-stroking the opposite cylinder to a minimum. This short-stroking is generally due to the fact that one engine or pump is packed looser than the other, in which event, other things being equal, the piston of one of the pumps will move somewhat faster than the other. By my improved valve gear the pumps are kept in step, and this is true, no matter what the position of the pistons may be when starting the pumps, as after one or two strokes, the pumps get into step and remain in step, one of the pumps always leading the other.

In the diagrammatic views of Figs. 7, 8, 9, 35 and 10, the positions of the synchronizing bar of the valve gear are illustrated. In Fig. 7, one of the engines is at the reversing point, and in Fig. 8, the other. In Figs. 9 and 10 the reversing at the opposite end of the 40 stroke is illustrated.

As previously stated, by my improved valve gear the engines are operated, and the liability of one short-stroking the other reduced to a minimum. It is evident from the foregoing description that one of the engines can be stopped for the purpose of repair or the like, and the other continue its operation and the same again connected and operated together very quickly and easily.

50 I have illustrated and described my improved valve gear in detail in the form preferred by me on account of its structural simplicity and convenience in operation, although I am aware that it is capable of considerable variation in structural details without departing from my invention.

Having thus described my invention, what I claim as new and desire to secure by Letters Patent, is:

60 1. The combination with a pair of engine cylinders of a pair of pumps; tie rods for said cylinders and pumps; valve stems; pivoted levers for actuating said valve stems, said valve stems having tappets arranged to be 65 engaged by said levers; a pair of sleeves slid-

ably mounted upon said tie rods; sleeves through which said levers are arranged, pivotally mounted on said sliding sleeves; a synchronizing bar; sleeves through which said bar is arranged, pivotally mounted on said 70 sliding sleeves; piston rods; brackets on said piston rods; sleeves through which said synchronizing bar is arranged, pivotally mounted on said brackets; and brackets on said tie rods, to which said last named sleeves may 75 be pivotally secured when disconnected, for the purpose specified.

2. The combination with a pair of engine cylinders of a pair of pumps; tie-rods for said cylinders and pumps; valve stems; pivoted 80 levers for actuating said valve stems, said valve stems having tappets arranged to be engaged by said levers; a pair of sleeves slidably mounted upon said tie rods; sleeves through which said levers are arranged, pivotally mounted on said sliding sleeves; a synchronizing bar; sleeves through which said bar is arranged, pivotally mounted on said 85 sliding sleeves; piston rods; brackets on said piston rods; and sleeves through which said 90 synchronizing bar is arranged, pivotally mounted on said brackets, for the purpose specified.

3. The combination with a pair of engine cylinders of a pair of pumps; tie-rods for said 95 cylinders and pumps; valve stems; pivoted levers for actuating said valve stems; a pair of sleeves slidably mounted upon said tie-rods; sleeves through which said levers are arranged, pivotally mounted on said sliding 100 sleeves; a synchronizing bar; sleeves through which said bar is arranged, pivotally mounted on said sliding sleeves; piston rods; sleeves through which said synchronizing bar is arranged, pivotally connected to said piston 105 rods; and brackets on said tie-rods, to which said last named sleeves may be pivotally secured when disconnected, for the purpose specified.

4. The combination with a pair of engine 110 cylinders of a pair of pumps; tie-rods for said cylinders and pumps; valve stems; pivoted levers for actuating said valve stems; a pair of sleeves slidably mounted upon said tie-rods; sleeves through which said levers are 115 arranged, pivotally mounted on said sliding sleeves; a synchronizing bar; sleeves through which said bar is arranged, pivotally mounted on said sliding sleeves; piston rods; and sleeves through which said synchronizing 120 bar is arranged, pivotally connected to said piston rods, for the purpose specified.

5. The combination with a pair of engine cylinders of the piston rods; valve stems; pivoted levers for actuating said valve 125 stems; a pair of reciprocating members; sleeves through which said levers are arranged, pivotally mounted on said reciprocating members; a synchronizing bar; sleeves through which said bar is arranged, pivotally 130

- mounted on said reciprocating members; sleeves through which said synchronizing bar is arranged, detachably secured to said piston rods by pivot pins; and means by 5 which said last named sleeves may be pivotally supported when disconnected from said piston rods, for the purpose specified.
6. The combination with a pair of engine cylinders of the piston rods; valve stems; 10 pivoted levers for actuating said valve stems; a pair of reciprocating members; sleeves through which said levers are arranged, pivotally mounted on said reciprocating members; a synchronizing bar; sleeves through 15 which said bar is arranged, pivotally mounted on said reciprocating members; and sleeves through which said synchronizing bar is arranged, pivotally secured to said piston rods, for the purpose specified.
- 20 7. The combination with a pair of engine cylinders of the piston rods and valve stems; a pair of reciprocating members for actuating said valve stems; a synchronizing bar; sleeves through which said bar is arranged, 25 pivotally mounted on said reciprocating members; sleeves through which said synchronizing bar is arranged, detachably secured to said piston rods by pivot pins; and means by which said last named sleeves may 30 be pivotally supported when disconnected from said piston rods, for the purpose specified.
8. The combination with a pair of engine cylinders of the piston rods and valve stems; 35 a pair of reciprocating members for actuating said valve stems; a synchronizing bar; sleeves through which said bar is arranged,

pivotally mounted on said reciprocating members; sleeves through which said synchronizing bar is arranged, pivotally secured 40 to said piston rods, for the purpose specified.

9. The combination with a pair of engine cylinders of the piston rods and valve stems; a synchronizing bar; means controlled thereby for actuating said valve stems; sleeves 45 through which said synchronizing bar is arranged, detachably secured to said piston rods by pivot pins; and means by which said sleeves may be pivotally supported when disconnected from said piston rods, for the 50 purpose specified.

10. The combination with a pair of engine cylinders of the piston rods and valve stems; a synchronizing bar; means controlled thereby for actuating said valve stems; and 55 sleeves through which said synchronizing bar is arranged, pivotally secured to said piston rods, for the purpose specified.

11. The combination with a pair of engine cylinders of the piston rods and valve stems; 60 a synchronizing bar; means controlled thereby for actuating said valve stems; means for pivotally securing said bar to said piston rods; and means for pivotally supporting either end of said bar when disconnected 65 from said piston rods, for the purpose specified.

In witness whereof, I have hereunto set my hand and seal in the presence of two witnesses.
